Des. 173,994
Patented Feb. 8, 1955

173,994

NARROW TEXTILE FABRIC OR THE LIKE

Curtis A. Limbach, Hartsdale, N. Y.

Application April 19, 1954, Serial No. 30,075

Term of patent 14 years

(Cl. D3—32)

To all whom it may concern:

Be it known that I, Curtis A. Limbach, a citizen of the United States, residing at Hartsdale, State of New York, have invented a new, original, and ornamental Design for a Narrow Textile Fabric or the like, of which the following is a specification, reference being had to the accompanying drawing, forming a part hereof.

The figure shows a piece of narrow textile fabric, showing my new design.

I claim:

The ornamental design for a narrow textile fabric or the like, as shown.
